UNITED STATES PATENT OFFICE.

JOSEPH D. WALLACE, OF CHAMPAIGN, ILLINOIS.

SELF-CLEANING STRAINER FOR SPRAYING-MACHINES.

No. 851,388.

Specification of Letters Patent.

Patented April 23, 1907.

Application filed April 18, 1906. Serial No. 312,330.

To all whom it may concern:

Be it known that I, JOSEPH D. WALLACE, a citizen of the United States, and a resident of the city of Champaign, county of Champaign, 5 and State of Illinois, have invented certain new and useful Improvements in Self-Cleaning Strainers for Spraying-Machines, of which the following is a specification.

This invention relates to devices for preventing the clogging of nozzles in sprayers or atomizers, having particularly in mind a self-cleaning device for the protection of nozzles in what are known as portable spraying machines, such as are employed for the application of various kinds of liquid insecticides to trees, plants, shrubs and the like, in orchards, gardens, fields, parks and boulevards. It is well known that these liquid compounds almost invariably contain a sediment 15 which tends, in use, to clog the nozzle and the valves employed, to the ultimate point of completely stopping the flow therethrough. It has been the practice, in some cases, to employ at a proper point in the supply duct 20 or conduit, a percolator or strainer, for the purpose of intercepting or arresting all except the very small particles of solid matter. These percolators or strainers themselves become foul or clogged in time and it is necessary to thoroughly clean them from time to time. This has been accomplished, among other ways, by changing the direction of the flow of water or other liquid through said strainer, which serves to wash away all solid 25 matter, which may, in some suitable manner, be discharged upon the ground. Heretofore, this cleaning operation has required a rather complicated system of valves, and devices of this class have on that account been, comparatively, both complicated and expensive.

The principal object of the present invention is to simplify the construction of devices of this character, and, in general, to produce a self-cleaning nozzle protector which will not only be simple in construction, but easily, quickly and conveniently operated, effective in results, and comparatively cheap in cost.

My invention will be more readily understood by reference to the accompanying drawings, forming a part of this specification, and in which

Figure 1 is a vertical, central, sectional elevation, of a device embodying my invention. Fig. 2 is a similar view of the material parts 55 thereof with the controlling valve in a different position of adjustment.

Referring now to the drawings in detail, numeral 3 refers to the main supply conduit or pipe, leading from the reservoir (not shown) within which a liquid to be sprayed is confined under pressure. The pipe 3 terminates in a valve 4 controlling the flow to and through the passages in the two branch pipes 5 and 6. The pipe 6 is properly a continuation of the main supply pipe 3, and is joined to its extension 7 by a union comprising the two parts 8 and 9, screw-threaded to the pipe-ends and to each other. This construction permits of the insertion of a removable strainer or percolator 10, which is firmly held between the two parts 8 and 9 of the union. With the valve 4 open, as shown in Fig. 1, the liquid will pass from the pipe 3 into the pipe 6, and up through the strainer 10, the pipe 7, and the T-fitting 11 to the hose-plugs 12, final discharge being controlled by a stop-cock 13.

The pipe 5 is the first of a series of common and well known pipe fittings, the last being the section 14 leading into the T-branch 11, 80 which provides a shunt conduit around the strainer 10.

The valve 4 is of rotary type and comprises in addition to the usual two-way plug 15, rotated by the usual lever 16, a side opening 17, to which may be fitted any desired form of final discharge pipe, such as the short section 18. The plug 15 is provided, in addition to the two-way valve passage 19, with the passage 20. When the plug 15 is in the 90 position indicated in Fig. 1, there is open communication from the pipe 3 to the pipe 6, and thence through the strainer 10 to the hose-plugs 12 and on to the spraying nozzles (not shown). Upon a quarter turn of the 95 cock, as shown in Fig. 2, communication is opened from the pipe 3 to the pipe 5, while the pipe 6 is closed, so far as direct discharge from the pipe 3 is concerned, but opened, through the passage 20, to the side opening 17. 100

It will be apparent that when the device is in use, and the valve-plug 15 in the position indicated in Fig. 1, the liquid from the supply pipe 3 will pass uninterruptedly through the pipe 6 and the strainer 10 to the nozzles, as shown by the arrows. When the strainer becomes foul or clogged, and it is desired to clean the same, the operator gives the lever 16 operating the valve-plug 15 a quarter turn, which closes the passage to the pipe 6, 105 directing the liquid around the loop and in a reverse direction through the strainer 10, 110

carrying with it all sediment and solid matter which has accumulated on the under side of said strainer, and out through the passage 20 and the side opening 17 of the valve 4, 5 from thence it is discharged upon the ground.

Not only is there required but a single operation of movement to manipulate the valve 4 and clean the strainer, but the cleaning operation itself requires but a moment of 10 time, the liquid being under full pressure. And not only is the operation short, thorough and effective, but the device itself may be located within easy reach of the operator or driver of the spraying machine—if applied 15 to a device of this character.

Many modifications of minor details of my improved nozzle protector will doubtless readily suggest themselves to those skilled in the art to which it appertains, and I therefore do not desire to limit my invention to the specific construction herein shown and described.

Having thus described my invention, I claim as new and desire to secure by Letters 25 Patent:

1. A self-cleaning straining device for spraying machines comprising a pipe having two reunited branches, one thereof being normally closed and the other provided with 30 a strainer and a normally closed vent on the pressure side of said strainer, and means for simultaneously closing said last-mentioned branch and opening said first-mentioned branch and said vent.

35 2. In a self-cleaning straining device for spraying machines, the combination, with a pipe having two reunited branches, one

thereof being provided with means for straining a liquid passing therethrough and a normally closed vent on the pressure side of said 40 straining means, of a valve normally directing the entire flow through said straining branch and operable to direct the entire flow through the other branch and open said vent.

3. A self-cleaning straining device for 45 spraying machines comprising a main conduit provided with a strainer and a normally closed discharge vent on the pressure side of said strainer, a normally closed shunt conduit around said strainer, and means for 50 directing the entire flow through said shunt conduit and opening said vent at one operation.

4. In a self-cleaning straining device for spraying machines, the combination, with a 55 normally open main conduit provided with means for straining a liquid passing therethrough and a normally closed vent on the pressure side of said straining means, of a normally closed shunt conduit around said 60 straining means and communicating at each end with said main conduit, and a valve at the branch of said main and shunt conduits adapted at one operation to close said main conduit and open said shunt conduit and 65 said vent.

In witness whereof, I have signed my name to the foregoing specification in the presence of two subscribing witnesses.

JOSEPH D. WALLACE.
